ATTORNEY

UNITED STATES PATENT OFFICE.

ANGELO CUOMO, OF ASTORIA, NEW YORK.

MILK-BOTTLE TOP.

1,374,719.

Specification of Letters Patent. Patented Apr. 12, 1921.

Application filed July 14, 1920. Serial No. 396,238.

To all whom it may concern:

Be it known that I, ANGELO CUOMO, a citizen of the United States, residing at Astoria, county of Queens, Long Island, State of New York, have invented certain new and useful Improvements in Milk-Bottle Tops, fully described and represented in the following specification and the accompanying drawings, forming a part of the same.

10 This invention relates to closures for bottles, and particularly to that class of closures adapted for temporary use in connection with milk bottles.

It is the especial object of the invention to provide a device of this character which shall be simple and economical to manufacture, durable, and capable of perfecting an air-tight closure of receptacles having necks of varying size, such as milk bottles, where 20 slight variations, due to faulty manufacture, usually occur.

For a full understanding of the invention, a detailed description of a construction embodying the invention in its preferred form, 25 and designed especially for use in connection with milk bottles, will now be given in connection with the accompanying drawings forming a part of this specification, and the features forming the invention then specifically pointed out in the claims.

In the drawings—

Figure 1 is a central section of the device; Fig. 2 is a top plan view, and

Fig. 3 is a bottom plan view of the circumferential neck band.

Referring now to the drawing, and especially Fig. 1, the device consists of a tubular cap piece 1 having secured to its base an annular rubber apron or flexible washer 2, 40 and forming in effect the bottle mouth engaging portion of the cap piece 1, such washer being secured between a flange 3, preferably formed integral with the cap piece 1, and a collar 4 forming a support or 45 backing therefor when the device is in position on a bottle mouth. Loosely mounted on the cap piece 1 is an annular plate or collar 5. Between this plate 5 and collar 4, and encircling the cap piece 1, is a spiral 50 spring 6 which exerts its force to keep the annular plate 5 and collar 4 separated.

In order that the cap piece with the parts mounted thereon as above described may be securely fastened to the bottle neck, I provide a circumferential bottle-neck band 7, 55 having finger holds 8 on each end thereof,

and an opening 9 and lug 10 on its respective ends to enable such band to be locked about the bottle neck. The neck band 7 is secured to the annular plate 5 by links or 60 chains 11.

It will be obvious from the foregoing that by so linking the annular plate 5 to the neck band 7, the pressure exerted by thus compressing spring 6 will push the cap piece 1 65 tightly onto the mouth of the bottle, the rubber washer or apron 2 providing an efficient sealing means at this point in case of any unevenness in the bottle or receptacle to which the device may be applied.

The cap piece 1 is provided on its upper part with an upwardly extending tubular spout 12, and in order to facilitate pouring and prevent bubbling of the liquid, I provide in the pouring orifice a small tube 13, 75 the upper open end of which is flush with the pouring orifice, and its opposite end being bent around on itself as at 14 (Fig. 1). With the tube thus arranged, the air entering the upper end of the tube 13 to displace 80 the liquid poured will have ready access to the bottle, thereby preventing the formation of a partial vacuum and consequent bubbling, and enabling a smooth even stream of liquid to flow from the spout. The pouring 85 orifice is covered by a hinged spring-actuated cap 15 having a spring or snap catch 16 of any well known construction, the cap 15 preferably being lined with a suitable flexible material, such as rubber, 17 adapted to 90 engage an annular flange 19 when the cover is closed and thus form an air-tight joint.

While the construction shown and described is a preferred one, it will be understood that certain changes and variations 95 may be made as to the details without departing from the invention.

What I claim is:

1. A bottle cap comprising a circumferential neck band, a spring pressed cap piece 100 having a pouring orifice and cover therefor, a movable member and a rigid member mounted on said cap piece, a spring supported by said cap piece and normally tending to separate said members, links between 105 the neck band and movable member to increase the tension of said spring when the device is in use, and means in the pouring orifice to prevent bubbling of the poured liquid.

2. A bottle cap comprising a circumferential neck band, a spring pressed bottle cap

having a pouring orifice, a hinged cover for said orifice, a snap lock for said cover, a movable member and a rigid member carried by said bottle cap, springs between said members normally tending to separate them, connections between the neck band and the movable member and adapted to maintain the bottle cap in position under spring tension, and an air inlet tube positioned in the 10 pouring orifice.

3. A bottle closure comprising a cap piece, a flexible washer and rigid backing plate therefor secured to said cap piece, an annular plate loosely mounted on said cap piece, 15 a coil spring encircling said cap piece and normally exerting its pressure to separate the annular plate and washer backing plate, a circumferential bottle neck band linked to said annular plate, a tubular spout formed 20 on said cap piece, a cover therefor, and an air inlet tube located in said spout.

4. A bottle closure comprising a cap piece, a washer and backing therefore secured to said cap piece, an annular plate loosely 25 mounted on said cap piece, a spring supported by said cap piece and normally sepa-

rating said annular plate and washer backing, a bottle neck band, links connecting said band and annular plate, a spout formed on said cap piece, a spring cover for said spout, 30 liquid sealing means carried by said cover, and a spring latch therefor.

5. A temporary bottle closure comprising a cap piece having a pouring spout, a collar loosely mounted on said cap piece, a spring mounted on said cap piece, a bottle neck band, and connections from the neck band to said loose collar for holding said spring under compression.

6. A temporary bottle closure comprising 40 a cap piece having a pouring orifice covered by a spring actuated cap, a collar loosely mounted on said cap piece, a spring encircling said cap piece, a bottle neck band and connections therefrom to said loose collar 45 normally holding said spring under compression, and an air inlet tube disposed in the pouring orifice.

In testimony whereof I have hereunto set my hand.

ANGELO CUOMO.
